CLAIM

The ornamental design for a package for a data storing device for a kitchen appliance, as shown and described.

DESCRIPTION

FIG. 1 is a side view of a package for a data storage device for a kitchen appliance according to the present design;

FIG. 2 is a top plan view thereof;

FIG. 3 is a front view thereof;

FIG. 4 is a back view thereof;

FIG. 5 is a second side view thereof; and,

FIG. 6 is a top perspective view thereof in an open position.
